A. PELESKEY.

FENCEPOST.

APPLICATION FILED JUNE 3, 1921.

1,420,140.

Patented June 20, 1922.

FIG. 1

UNITED STATES PATENT OFFICE.

ANDREW PELESKEY, OF MARTINS FERRY, OHIO.

FENCEPOST.

1,420,140.

Specification of Letters Patent. Patented June 20, 1922.

Application filed June 3, 1921. Serial No. 474,843.

To all whom it may concern:

Be it known that I, ANDREW PELESKEY, a citizen of Hungary, residing at Martins Ferry, in the county of Belmont and State of Ohio, have invented certain new and useful Improvements in Fenceposts, of which the following is a specification.

This invention relates generally to the construction of fences, having more particularly reference to the construction of the posts of wire fences.

The invention has for an object to provide a novel and simple type of post to which the wire can be readily attached, both when the post is at the end of the fence and when it is intermediate the ends.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view of a portion of a fence constructed according to the invention.

Fig. 2 is a horizontal section taken on the plane indicated by the line 2—2 of Fig. 1.

Fig. 3 shows a modified form of plate member for holding the wires to intermediate posts.

Referring now to the drawings, the main body of the post is indicated at 10 and is formed with a pointed lower end 11 adapted to be driven, or otherwise inserted, into the ground.

The outer face of the post is formed with a recess 12 which extends completely there-across, terminating at upper and lower ends a short distance from the top of the post and the pointed extremity 11.

This recess 12 is filled by a removable section 13 which is bolted in place by the bolts 14, co-operating tongue and groove elements 15 being formed on the bottom of the section 13 and the adjacent wall of the recess 12.

This construction permits of the securing of the horizontal fence wires to the posts in such manner as may be desired. For instance, I have shown one more wire 15'

wound several times around the section 13 as indicated at 16, the end of the wire being caught between the adjacent faces of the section and the main body of the post.

55

A second wire 17 is wound first around the section 13 as at 18, and then around the main element 10 as at 19, while a third wire 20 is wound around the complete post with its 60 end inturned between the parts 10 and 13. The post members 10 and 13 may be cut out at the corners as at 22 to accommodate the wires.

60

Upon the face of the section I provide a 65 series of elements with which wires 25 may be engaged to prevent displacement when the posts are employed intermediate the ends of the fence. These elements comprise plates 26 secured by screws 27 to the section 70 13 and having their edges notched to form a series of ears 28 which may be bent vertically to project on opposite sides of the wire.

In Fig. 3 I have indicated an arrangement in which the notches in the plate 30 are cut 75 in a manner to have the bases of the ears 31 diagonal to the wire 32 so that when the wire has been passed between a pair of these ears the latter can be bent down to overlap the wire as shown.

80

Having thus described my invention what I claim as new and desire to protect by Letters Patent of the United States is as follows:

1. In a fence, a post, a flat plate secured 85 to the face of said post, and a wire extending across said plate in contact therewith, said plate having its side edges notched to form a plurality of ears arranged in pairs on opposite sides thereof and bent outwardly 90 from the body of the plate to receive the wire between the respective ears of each pair and prevent vertical displacement thereof.

2. A fence post having on the face thereof a series of plates notched on the edges 95 to form co-operating pairs of ears adapted to be bent outwardly to receive a wire there-between, said ears having diagonally arranged bases, for the purpose specified.

In testimony whereof I have affixed my 100 signature.

ANDREW PELESKEY.
